SIMON LAKE, OF MILFORD, CONNECTICUT.

APPARATUS FOR RIVET-SETTING AND SIMILAR OPERATIONS.

1,337,457.

Specification of Letters Patent. Patented Apr. 20, 1920.

Application filed December 5, 1919. Serial No. 342,694.

To all whom it may concern:

Be it known that I, SIMON LAKE, a citizen of the United States, residing at Milford, in the county of New Haven and State 5 of Connecticut, have invented a certain new and useful Improvement in Apparatus for Rivet-Setting and Similar Operations, of which the following it a full, clear, and exact description.

- 10 10 This invention relates to apparatus for performing rivet-setting and similar operations such as spot-welding, and is intended to facilitate such operations when conducted over large areas and with heavy tools.
- 15 15 One of the objects of the invention based on this intention is the production of a tool-supporting device which will facilitate the handling of heavy and cumbersome tools during their manipulation.
- 20 20 Another object is to provide such a tool-supporting device adapted to support, in addition to the weight of the tools, the weight of the cables, tubes, hose and the like which supply the tool operating media.
- 25 25 The invention consists in carrying the tools for performing the operations of rivet-heating, heading, etc. by an arm capable of pivotal action on its support, the support in turn being pivotally mounted, and capable 30 30 of being extended longitudinally, and the tools being so mounted on the arm as to have a pivotal action in both horizontal and vertical directions, the combination of all of these pivotal and swiveling actions making 35 35 possible a universal movement of the tools independently in all directions, and the extensibility of the arm providing for operating over a large area to the end that the desired operations may be performed with 40 40 ease and expedition. And the invention also contemplates various details of construction and arrangements of parts, including means for proper relative positioning of tools on opposite sides of a structure, all 45 45 as I will proceed now to explain and finally claim.

In the accompanying drawings illustrating the invention, in the several figures of which like parts are similarly designated, 50 50 Figure 1 is a plan view of the apparatus of the invention and showing the heating tool and the parts operated upon in section; Fig. 2 is an elevation of the apparatus; Fig. 3 is a section taken in the plane of line 3—3 55 55 of Fig. 1; Fig. 4 is an end view of the sup-

port and arm and electrical connections looking toward the left-hand end of Fig. 1, parts being removed. Fig. 5 is a section taken on line 5—5 of Fig. 4. Fig. 6 is an end view of some of the parts looking toward the right-hand end of Fig. 1; Figs. 7 and 8 show schematic elevational and end views of the apparatus and its method of mounting and operation; and Fig. 9 shows a modification wherein two heating elements are used for the purpose of forming a simple spot-weld. 60 65

Referring more particularly to the drawings, a stand or support 1 is provided whereby the whole of the operating mechanism 70 upon one side of the structure operated upon may be supported, the stand being provided with suitable attaching means such as bolts 2, and adapted to be insulated from the structure. This stand is provided with a 75 projection or stud 3 upon which is rotatably mounted a bracket 4, having a set-screw 5 working in an annular groove 6 in stud 3 whereby the bracket is held in fixed rotative adjustment on the stud. This bracket carries a yoke 7 pivoted on it by means of a pin 8 and in journals 9 in the ends of the arms 10 of the yoke is mounted for pivotal action, within the limits set by the base 11 of the yoke, an extensible tool-carrying arm 12, 80 85 preferably of the lazy-tongs variety, and provided at intervals throughout its length with members 13 which are connected to it, and, in addition to acting as stiffening and spacing members for the plurality of lazy-tongs elements 14 of the arm, also serve as guides and supports for devices hereinafter described. 90

At the ends of the arm 12 are carried heads 15, 15', the head 15 provided with a 95 support 16 upon which are mounted any desired or required number of counterweights 17. The head 15' is provided with a stud 18 upon which is revolvably mounted a tool-carrying member 19 carrying in swivel-bearings 20 a pressure tool or element 21, such as an automatic hammer, here shown as an ordinary air hammer. At the outer end of this member 19 is revolvably mounted a yoke 22 between the arms of which is 105 pivoted a heating element or tool 23. The member 19 and yoke 22 are suitably secured in revolvable relation to the stud 18 and each other, respectively, by set-screws 24 engaging suitable annular grooves 25. 110

The heating element here shown is an electrical heating tool, having a frame 26 by means of which it is mounted in the yoke 22 and this frame carries a furnace head 27 between which and one end of the frame are mounted rods 28 upon which is supported a slidable member 29 engaging an electrode 30 of carbon or the like. The electrode 30 is so arranged as to have an arc-forming movement with relation to a heater disk 31, and the length of the arc is regulated by means of an adjustable stop 32 carried by one of the rods 28 and adjustable by means of a threaded shaft 33, its adjusted position being fixed by means of a set-screw 34. The member 29 abuts against this stop 32 and is backed up by a spring 35. It will thus be seen that when the handle 36 of member 29 is grasped and the member moved so as to compress the spring 35, the electrode 30 will be moved into contact with disk 31 to form a circuit, and when the handle 36 is released the spring 35 will force the member 29 back against the stop 32 and the electrode 30 will be simultaneously moved back and away from disk 31 thus forming an arc between these parts.

Referring particularly to Fig. 1, the disk 31 is provided with a short tube 37 of refractory material adapted to receive and heat the projecting end of a rivet as shown, an area of the parts around the rivet being heated by the body of the disk which with the tube 37 is heated to a white heat by the arc.

The head 27 is provided with a refractory lining 38 and a substantially transparent member 39 with which latter communicate sight openings 40 through which conditions in the furnace chamber may be inspected.

In the modification shown in Fig. 9 where the heaters are designed for use as spot-welders only, the short tube 37 is replaced by a solid replaceable plug 41.

Current is supplied to the heating tool by means of a lead 42 connected with a terminal 43 insulated at 44 from the stand 1 and provided with a brush-member 45 in contact with a contact ring 46 mounted on 50 and rotating with the bracket 4 but insulated from it at 47. Current is taken from this ring by a cable 48 connected with a member 49 which in turn is connected with a conductor 50 formed of a plurality of telescoping tubes or the like carried by the members 13 in openings 51 therein provided with suitable insulating bushings 52. Current is taken off of this conductor 50 at the tool-carrying end of the arm by a member 53 provided with a cable or the like 54 connected with the electrode 30 as shown at 55.

Referring particularly to Figs. 7 and 8, it will be seen that the tools when mounted upon the structure operated upon by means 65 of the extensible arm and its stand are

capable of operating movement over a large area of the structure, as indicated by the arcs shown in broken lines, which indicate substantially the complete extended and retracted positions of the arm.

In the use of devices of this character upon large structures, such as ships, where the surface operated upon is forty more or less feet in height, it is absolutely essential for effective operation that some means be provided whereby the operators upon opposite sides of the structure may know the positions of each other's tools, and to this end I provide the chain sprocket and weight mechanism illustrated schematically in Figs. 70 7 and 8. In this mechanism I use a shaft 56 adapted to be inserted through any convenient hole in the structure, such as a rivet hole, and upon the opposite ends of the shaft I mount for fixed rotation therewith sprockets 57 which must necessarily therefore turn together. Over these sprockets I run chains 58 connected at one end to the arms 12, their other ends being provided with weights 59. In using this positioning device the arms 12 75 will be so counterweighted at 16 as to have their tool-carrying ends heavy enough to exert a normal lifting force upon the weights 59 thus tending always to exert a tension upon the chains 58. The operators 80 knowing before hand, by signals or the like, what particular line of rivets or joint of plates they are working upon they will follow this line, the correct point on the line being determined by the extent to which the chains 85 58 and with them the sprockets 57 are moved, and so long as the operators keep their chains taut the tools with which they are operating will always be directly opposite each other, and a movement of one will, 90 through the rotation of its sprocket, impart a corresponding motion to the other by causing a corresponding rotation of its sprocket.

It will be seen that the tool-carrying arm 110 12 is so pivoted in the yoke 7 that the length of the arm from this pivot to its tool-carrying end is approximately twice its length from the pivot to the counter-weight-carrying end, thereby necessitating the use of 105 counterweights approximately twice as heavy as the weight of the tool-carrying end plus the weight of the tools to balance the arm. It will also be seen that the last link 115 of the lazy-tongs at the weighted end of the arm has links of one-half the radial length of the other links of the arm whereby a corresponding equilibrium of the arm is obtained when in a vertical position.

By this arrangement I am enabled to provide an extension of the tool-carrying end of the arm double that of the weight-carrying end, whereby interference of the weight-carrying end with scaffolding and the like is minimized.

For stiffening the extreme ends of the arm I provide short rods 62 attached to the heads 15, 15' and having sliding engagement with the members 13 in holes 63.

5 The manner of using my apparatus is substantially as follows:—Assuming that the stand 1 has been properly bolted to the structure, such as the side or bottom of a ship, as shown in Figs. 7 and 8, and that the 10 electrical devices are properly connected with a source of electrical energy, and the setting of rivets is the work in hand, the operators on opposite sides of the structure locate their tools in proper relation. A rivet 15 is then inserted in the holes provided for it in the plates. The operator manipulating the anvil or holding tool 60 will then place his tool over the head of the rivet and the operator on the other side will position 20 his heating tool over the rivet so that the projecting end 61 of the rivet will enter the tube 37. He then operates handle 36 to move electrode 30 into contact with disk 31. This establishes a circuit between the two 25 tools through the rivet and when handle 36 is released the electrode will move back and form an arc which will heat the rivet and surrounding parts to a welding heat, as previously described. When such a heat has 30 been attained the heating tool is removed and the rivet and parts heated hammered with the hammer, thus producing heading of the rivet and welding of the parts and rivet.

35 The use of the device in a spot-welding operation where tools as shown in Fig. 9 are used, is substantially the same, except that the heating tools are moved step by step along the joint to be welded, the spots heated being immediately after the heating operation acted upon by the hammers on both sides.

It will therefore be seen that I provide 40 means whereby riveting and welding operations may be performed with heavy, cumbersome, portable tools without taxing the strength of the operator or causing him any inconvenience in manipulating them.

The tools are so mounted as to have a 45 practically universal movement within a wide radius, and, when operations within this radius are completed, the stand and its attached parts, including the tools, may be placed in a new position and the operator 55 thereby afforded a new radius of operation.

Such operations as those just described except where light work only was performed, could not heretofore be performed upon a fixed structure with portable tools owing to 60 the great weight of such tools and the necessary feed wires and hose connected therewith, but by the use of my invention these operations are made possible because all of the weight of the tools and other devices is 65 mechanically supported, and supported in

such a flexible manner as to be as easy of manipulation as are light tools in the hands of an operator.

It is to be understood that the invention is not limited to the specific embodiment shown 70 and described as it is possible that various changes in details of construction and arrangement of parts are within the spirit of the invention and the scope of the following claims. 75

What I claim is:—

1. In an apparatus for rivet-setting and the like, a heating element, a pressure-applying element, and an extensible swiveling support for these elements whereby they 80 may be brought into and supported in operative relation to the work.

2. In an apparatus for rivet-setting and the like, a heating element, a pressure-applying element, and an extensible counter-weighted swiveling support for these elements whereby they may be brought into operative relation to the work and supported in such relation during operation. 85

3. In an apparatus for rivet-setting and the like, a rivet heating tool, a rivet heading tool, and a support for these tools whereby they may be supported for independent movement relative to each other in operative 90 relation to the work. 95

4. In an apparatus for rivet-setting and the like, the combination with a tool support mounted for movement relative to the work, of a tool mounted thereon and carried thereby and capable of universal movement relative thereto. 100

5. In an apparatus for rivet-setting and the like, the combination with a tool support movable relative to the work, of tools mounted thereon and universally movable 105 relative thereto and to each other.

6. In an apparatus for rivet-setting and the like, the combination with a revolvably mounted tool support including an extensible counter balanced arm pivoted on an axis normal to the axis of revolution of said support, of tools carried by said arm and movable relative thereto and to each other. 110

7. In an apparatus for rivet-setting and the like, the combination with a revolvably mounted tool support carrying an extensible counterweighted arm pivoted on an axis normal to the axis of revolution of said support, of a heating tool and a pressure tool carried by said arm and movable relative thereto and to each other. 115

8. In an apparatus for rivet-setting and the like, the combination with a tool support having an extensible arm, of a rivet-heating element and a rivet-heading element carried by said arm, and means connected with said heating element and supported by said arm for conducting a heat-producing medium to said heating element. 125

9. In apparatus for rivet-setting and the 130

- like, the combination with an extensible counterweighted arm of an electric heating element carried thereby, and means connected with said heating element and carried 5 by said arm for supplying electrical energy to said electric heating element.
10. In an apparatus for rivet-setting and the like, the combination with an extensible tool carrying arm, of an electric heating 10 tool carried thereby, and a telescoping conductor carried by said arm and extensible therewith for supplying electrical energy to said heating element.
11. In an apparatus for rivet-setting and 15 the like, a rivet heating tool, a rivet heading tool, an arm for supporting said tools and so formed as to permit of ready manipulation of the tools within a fixed area, and means for holding a rivet in fixed relation 20 to said heating and heading tools during the operation of each of them.
12. In an apparatus for rivet-setting and the like, the combination with a support adapted to be attached to the parts to be 25 operated upon and provided with an extensible tool-carrying arm, of a rivet-heating tool and a rivet-heading tool carried thereby and movable relative thereto and to each other, whereby by the extensibility of 30 said arm and the relative movements of said tools the tools may be brought manually into proper operating position while they are supported by said arm.
13. In an apparatus for rivet-setting and 35 the like, a swiveling support, an extensible arm pivoted thereon in a plane normal to the swiveling axis thereof, and a tool carried by said arm and movable relative thereto in both horizontal and vertical directions, 40 whereby by the combined means of its own movements and those of the arm and its support, a limited movement in all directions is afforded said tool.
14. In an apparatus for rivet-setting and 45 the like, an arm composed of a plurality of lazy-tongs members so arranged as to provide a substantially laterally rigid but longitudinally extensible member.
15. In an apparatus for rivet-setting and 50 the like, an arm composed of a plurality of laterally rigid but longitudinally extensible members so arranged as to produce a rigid extensible structure.
16. In an apparatus for rivet-setting and 55 the like, an arm composed of four longi-
- tudinally extensible laterally rigid members so arranged as to form a hollow square, and spacing members arranged at intervals transversely thereof.
17. In an apparatus for rivet-setting and 60 the like, an arm composed of a plurality of longitudinally extensible members, and an extensible conductor carried thereby and extensible therewith.
18. In an apparatus for rivet-setting and 65 the like, an arm composed of a plurality of longitudinally extensible members, spacing members arranged at intervals transversely throughout the length thereof, and a conductor mounted in said spacing members 70 and carried thereby and extensible with said extensible members.
19. In an apparatus for rivet-setting and the like, the combination with a pair of independent tool carrying arms operating 75 upon opposite sides of a structure, of means for maintaining said arms in proper relative position.
20. In an apparatus for rivet-setting and the like, the combination with a pair of independent tool-carriers working together, of interconnected means for maintaining said carriers in proper relative adjustment. 80
21. In an apparatus for rivet-setting and the like, the combination with a pair of tool-carriers, of means for maintaining said carriers in proper relative adjustment including a chain and weight mechanism attached 85 to each carrier and interconnected.
22. In an apparatus for rivet-setting and 90 the like, the combination with a pair of independent tool-carriers, of mechanism attached to each carrier and inter-connected, whereby the tools of said carriers will be maintained in proper operative relation. 95
23. In an apparatus for rivet-setting and the like, the combination with a pair of tool-carriers, of means comprising weighted members attached to each carrier, and intercommunicating mechanism between said 100 members, whereby movement of one carrier will cause a corresponding relative movement of the other carrier.

In testimony whereof I have hereunto set my hand this 1st day of December A. D. 105 1919.

SIMON LAKE.
